(57) **CLAIM**

The ornamental design for a flower pack, as shown and described.

DESCRIPTION

FIG. 1 is a plan view of a flower pack showing our new design as a blank in unfolded condition with the broken lines representing fold lines;

FIG. 2 is a perspective view thereof in partially assembled condition;

FIG. 3 is a perspective view thereof in further assembled condition;

FIG. 4 is a perspective view thereof in fully assembled condition;

FIG. 5 is a front view thereof;

FIG. 6 is a rear view thereof;

FIG. 7 is a top plan view thereof;

FIG. 8 is a bottom view thereof;

FIG. 9 is a side view thereof; and,

FIG. 10 is an opposite side view thereof.
